UNITED STATES PATENT OFFICE.

HOMER LEE, OF NEW YORK, N. Y.

INTAGLIO PRINT.

1,299,484.

Specification of Letters Patent. Patented Apr. 8, 1919.

Application filed June 18, 1915. Serial No. 34,822.

To all whom it may concern:

Be it known that I, HOMER LEE, a citizen of the United States, and resident of New York city, county of New York, and State 5 of New York, have invented an Improvement in Intaglio Prints, of which the following is a specification.

The object of my invention is to provide a method and result in intaglio printing, 10 more especially as employed in bank notes, Government notes, stocks and bonds, whereby attempts at reproduction by forgery are not possible.

At the present time, certain methods have 15 been devised wherein intaglio printed matter may be reproduced with all of the accuracy of the original, not only as to size, definition, intensity, and accuracy, but also as to the peculiarities in respect to the cut- 20 tings of the graver tool in the original, which may all be reproduced with faithful accuracy, and this too, without the employment of photography, hand-engraving or any necessity of costly appliances. So per- 25 fect is the reproduction possible that experts are not able to distinguish the difference be- 30 tween the original and the reproduction. As such reproduction makes forgery within easy accomplishment of a man of ordinary 35 intelligence and without the necessity of costly appliances such as required in photo- engraving and photo-mechanical processes, it becomes vitally necessary to provide some 40 means whereby reproduced intaglio print- 45 ing by forgery can be prevented and hence make it impossible for forgers to utilize 50 their knowledge in attempted production of spurious bank notes, bonds, stocks, etc.

Intaglio printing whether performed by 45 mechanical devices or by hand-engraving, provides cuts of more or less deepness, and which in cases of extended black areas are widened by numerous cuts of the graver which produces a more or less roughened bottom to 55 the depression. The ink is forced into the recesses thus engraved in the polished surface of the plate, and after the plate has had the unengraved surfaces cleaned of ink, an impression is taken by pressing the paper upon the plate and causing the ink within 60 the grooves and recesses to adhere to the surface of the paper, and to adhere to and be removed by the paper when the same is stripped from the plate. The ink thus re- 65 moved will be found to constitute ridges of

various widths, shapes and depths arranged in the inverse form to the recesses or depressions cut into the plate, and having upon its surface all of the characteristics of the engraved surfaces in the plate. If a reproduction were to be made by hand-work, it is manifest that the same cuttings would hardly be possible, and therefore an accurate counterpart could not be made by hand- 60 engraving processes. It is possible, how- 65 ever, as above pointed out, to so reproduce not only the surface arrangement of the ink upon the paper, but also to reproduce these ridges in cross section with definite accuracy, that some means must be provided to 70 insure the safety of financial paper against the acts of forgers who may become pos- 75 sessed with an intimate knowledge of these lately developed methods of reproduction, and it is the primary object of my present 80 invention to so carry out the act of printing in intaglio that a reproduction by counter- feiting of the said intaglio printing will fail of its purpose by reason of the fact that a true reproduction in appearance to the eye 85 could not be made. On the other hand, an attempted reproduction will produce a plate, the printing from which will be so disfigured as compared to the artistic finish of the 90 original printing, that no serious compari- 95 son could be made of the two but that the most ignorant person would readily recog- nize the attempted forgery; so pronounced is this that no forger would even attempt to resort to a forgery under such circum- 95 stances.

That my invention may be better under- 100 stood, and its distinction over the prior method of intaglio printing be appreciated, I will first briefly indicate the method of 105 making forged reproductions from intaglio work, and then point out how my improve- 110 ments may prevent the possibility of such forgery:—

In making a reproduction, the ink of the 100 intaglio print is by certain methods trans- 105 ferred upon a glass plate and all of the paper which formerly held the lines removed. The transparency thus formed of the exact in- 110 taglio ink lines which formerly were upon the paper is then employed in forming a metal plate of the exact counterpart; and for obvious reasons I do not here enter into the details of this process of the making of the transparency and the preparation of the 110

plate, as such general disclosures would be against public policy.

My invention will be better understood by reference to the drawings, in which:

5 Figure 1 is a plan view of a portion of a sheet printed in intaglio embodying my invention; and Fig. 2 is a cross section, greatly enlarged, through a sheet of paper and indicating thereon the various intaglio printings embodying my invention.

10 In carrying out my improved process of intaglio printing, I cause to be laid upon the paper two impressions from two plates both by intaglio printing, and hence both

15 laying raised lines of pigment upon the surface of the paper, said lines of one printing being superimposed upon the lines of the other; but in so doing, the lines B of the first impression are made in a substantially 20 white or practically invisible pigment, and moreover are preferably of a fine design which would largely cover the surface of the paper A, whereas the lines C, C', C'', of the second printing deposits upon the paper

25 and previously printed surfaces of the white or invisible pigment B and constitutes the bold intaglio printing including all of the vignette, machine borders, script and other marks of designation required for the particular "security" which is intended to be represented by the printing. In this manner, the artistic design of the printing such as is now carried on in printing securities, may be followed in all of its detail, as the

35 substantially white or practically invisible intaglio printing forming the base or ground over which the secondary printing is made in no way interferes with the artistic finish as a whole. The structural effect, however, of the invisible printing B upon the paper is present so that when any attempt is made to transfer the intaglio printed lines of the security in making a reproduction or forgery, the plate which would be reproduced would contain not only the recesses

40 corresponding to the original plate from which the invisible printing was performed, but also recesses C, C', C'', etc., of the plate or plates from which the artistic and other printing was made to designate the nature and value of the "security", and it is therefore manifest that when a reproduced print is made from such a plate, the artistic design and particular words and figures designating the character of the security would be greatly marred and obliterated by the printing from the recessed portions corresponding to the invisible printing of the original; and this may be made to take place

45 to such an extent that the attempted reproduction would be so confused as to be hardly readable, this being purely dependent upon the character of the primary printing in the invisible pigment of the original.

60 65 The primary printing in the substantially

invisible pigment may be accomplished by the use of a large number of fine lines, so great in number that they would almost obliterate the design of the secondary printing when a spurious reproduction was attempted to be made in printing, and yet in the original these numerous fine lines would in no manner act as an objection and would not be noticed except by a close examination of the printed surface. Furthermore, the welding of the pigments used for the invisible printing and the bold printing is insured by reason of the fact that in modern intaglio work where several printings are required, whether back or front or different colors upon different portions, the paper after being once properly moistened is maintained in the moistened condition between printings by being placed between paraffin paper or pads which, while preventing the escape of the moisture, permit the inks to set sufficiently to permit the second or third printing without blurring. In the particular improvement forming the subject matter of this application, the second or bold printing over the invisible pigment of the first printing may be done while the said invisible pigment is still in a sufficiently plastic condition to readily weld into the pigment of the bold printing in black or dark color found on all securities. This welding of the pigments would make it practically impossible, even with the most laborious effort, for a forger to pick apart the deposited pigments in the attempt of reproduction.

70 75 80 85 90 95 100 105 110 115 120 125 130 In place of making a special plate for printing the invisible intaglio printing for each individual "security" which is to be made, the fact that because the pigment is white, cream or substantially invisible, or at least unobjectionable in so far as it may produce a tint to the surface of the paper, such intaglio ground to the paper may be made on the paper sheets or roll of paper as a preliminary operation and covering the entire surface thereof where the quantity of the work is large. In this manner the said preliminary printing would be less expensive and would provide a paper which may be subsequently cut up into the desired shapes for the various securities to be specially printed as may be required, and this preliminary printing of the entire surface of the paper may be done immediately before the paper is to be used in the subsequent printing operations so that the same moisture therein may be employed, or the said paper may be so prepared and subsequently employed at a later period by remoistening before the second printing, if so desired. When the paper is prepared in sheets or rolls in this manner with the invisible intaglio surface, this intaglio prepared surface will cover not only the artistic and bold printing in black or colors of the "security",

but will also extend to the extreme marginal edges of the "security" and thus make the reproduction by the attempted forgery radically different in its general appearance, 5 since the entire surface of the reproduction would be blurred and mottled by the printing due to reproduction of the invisible intaglio surface of the original. It is also to be understood that while I have referred 10 to the invisible intaglio printing as being in lines, it may be merely as a stipple work, and in this respect it may be so dense that the effect of the secondary printing would be almost entirely blotted out in any attempt 15 at forgery, and yet in the original printing the artistic finish of the present recognized type of steel and copper plate engraving would be present in all or substantially all of its beauty and sharpness.

20 While I have described my invention especially in connection with the intaglio white pigment or safety printing for use in connection with intaglio printing of bank notes, stocks, bonds, stamps, and other securities, 25 I wish also to be understood as employing the white or substantially invisible pigment intaglio printing as a means of guarding against forgery in cases where the bold or defining printing of the "security" is printed 30 in any suitable manner, whether wholly by intaglio or wholly by surface printing such as type or lithograph or combinations of intaglio and these, irrespective of the colors employed, as in all cases the white pigment 35 may be employed without deterioration of the other printing, and yet it would prevent the reproduction of intaglio duplicates without detection, and would enforce a combination of processes to be employed by the 40 forger to make the composite of both intaglio and surface printing in the "security," even where the intaglio printing did not of itself perform any definite function in the artistic design or designation of the character 45 of the "security." It will be noted that where the white pigment is printed as a base or ground, the surface printing would be imposed upon this intaglio ground and consequently would differ in material respects 50 from those cases where a surface printing was first made upon the paper and intaglio printing in black or color upon it. My invention is not to be limited by the particular modifications of the character of the printing 55 which is employed to designate the value or character of the "security," although its most effective advantages would no doubt be in the cases of where the character or value of the security was to be bold intaglio printing 60 in black or dark color or combinations of these, and which were underlaid with my improved substantially invisible intaglio printing.

Where I use the term strongly pronounced 65 color in the claims, I include therein dark

colors and black which are in great contrast to the ink of relatively invisible character which forms the under printing.

My improvements are equally useful in protecting specially printed railroad tickets, 70 revenue and custom stamps, cigar and cigarette and tobacco stamps, etc.

While I have referred to the primary printing as being done in a white or practically invisible pigment, it is also to be 75 understood that this pigment may be translucent instead of opaque if so desired, but while such translucency would not be of any appreciable benefit where the invisible printing was performed upon the paper as the 80 primary act, such translucency would, however, be of particular benefit where the principles of my invention were carried to the extent of being applied to existing "securities" which were required to be protected by 85 use of my present invention, for in this case the invisible printing would be printed upon the present black or other bold printing of the "security" and thereby provide the superimposed intaglio lines crossing each other in 90 such a manner that any attempt at reproducing the one will simultaneously reproduce the other, and then upon reproduction would produce the combination of the two in the bold printing and thus make forgery 95 impossible. In a case such as the reprinting of existing bonds or "securities" with a translucent or transparent pigment, the lines may be reasonably far apart and fine so as not to objectionably mar the brilliancy of 100 the original printing, but this is a matter to suit the wish of the owners of the "securities" and protection should in all cases dominate any aesthetic desire of the parties controlling the issue of the "securities."

I do not restrict myself to the particular character of the pigments employed, nor to the particular tints, but in the most preferred adaptation of my invention, the more invisible the pigment of the primary printing the more satisfactory will be the results, not only in respect to the prevention against forgery, but in permitting the most satisfactory and artistic effects to be maintained in the original intaglio work, while at the 115 same time insuring a maximum of security against forgery.

Having now described my invention, what I claim as new and desire to secure by Letters Patent, is:

1. A bank note, bond or other security, consisting of a sheet of paper having an underlying printing of light lines in intaglio and in a pigment of a relatively invisible character, and a superposed or overlying 125 printing of heavier lines in intaglio and in strongly pronounced color designating the nature of the security, said printing including the border vignettes and such other matter as may be required and in all parts under- 130

laid by the first stated printing in the pigment of relatively invisible character.

2. A bank note, bond or other security, consisting of a sheet of paper having two intaglio printings superposed one upon the other, the under printing being relatively unobtrusive to sight and not of a defining character and the upper printing including the border, vignettes and other designating matter being in strongly pronounced color and clearly defining as to the character of the security and further in every part underlaid by the first mentioned printing.

3. A bank note, bond, or other security,

having its surface printed in intaglio a plurality of times, the successive printings being superposed, one of said printings being in a translucent pigment and the remaining printing in strongly pronounced color to define the character of the security. 15

In testimony of which invention I hereunto set my hand. 20
